UNITED STATES PATENT OFFICE

146,794

DESIGN FOR A SCARF HOLDER

Paul L. Hartnett, Leominster, Mass.

Application December 22, 1945, Serial No. 124,953

Term of patent 3½ years

(Cl. D17—10)

To all whom it may concern:

Be it known that I, Paul L. Hartnett, a citizen of the United States, residing at Leominster, in the county of Worcester and State of Massachusetts, have invented a new, original, and ornamental Design for Scarf Holder, of which the following is a specification, reference being had to the accompanying drawing, forming part thereof.

Fig. 1 is a top plan view;
Fig. 2 is a view in end elevation;
Fig. 3 is a view in front elevation; and
Fig. 4 is a bottom plan view of a scarf holder showing my new design.

I claim:

The ornamental design for a scarf holder, as shown.

PAUL L. HARTNETT.
